E. F. RICHMAN, OF MUSCATINE, IOWA.

Letters Patent No. 74,187, dated February 4, 1868; antedated August 5, 1867.

IMPROVEMENT IN WOVEN FABRIC.

The Schedule referred to in these Letters Patent and making part of the same.

TO WHOM IT MAY CONCERN:

Be it known that I, E. F. RICHMAN, of Muscatine, in the county of Muscatine, and State of Iowa, have invented an Improved Fabric; and I do hereby declare that the following is a full, clear, and exact description thereof, reference being had to the accompanying drawings, making part of this specification, in which—

Figure 1 is a view of the improved fabric, composed of two thicknesses of woof or weft.

Figure 2 is an edge view of the same.

Figure 3 is an edge view, showing three layers of weft.

Similar letters of reference indicate corresponding parts in the several figures.

The nature of my invention consists in weaving any weaveable material double or of any desired thickness, in such a manner that the threads, parts, or pieces of one course or layer of the weft shall cover the interstices or spaces of the adjoining layer or layers lying either above or below it, thus breaking joints, and forming a fabric of closer texture, more impervious to dust, cold, water, and light, and more flexible than textures which are woven in the ordinary way, as will be hereinafter described.

My fabric has this peculiarity, that while every thread of weft has a thread of warp on each side, holding it fast in place the warp-threads all meander through the body of the fabric in such a way that each thread in succession rises to the upper surface thereof, and descends to its lower surface, so as to make the two surfaces substantially alike, showing no right or wrong sides, and binding the whole together in one compact and at the same time flexible fabric. All this will more fully appear by reference to the drawings, figs. 2 and 3.

To enable others skilled in the art to understand my invention more fully, I will describe more in detail the operation by which the fabric is formed.

There must always be one more heddle-leaf than the number of the intended layers or courses of the weft-threads in the fabric. Where there are to be two of these layers, there must be three heddles. I then take as many contiguous warp-threads as there are heddles, and pass one through each of the heddles in succession in corresponding heddle-frames. As many more contiguous warp-threads are then taken and passed in the same order through heddles in the corresponding frames, until the whole number of the warp-threads are thus passed through the heddles, an equal number through each. The threads are thus passed through the reeds in the usual way, and the weaving is ready to be commenced.

Contrivances well known to all weavers, can readily be arranged and operated in such a way as to open the shed to receive the weft-threads, in the order represented in figs. 2 and 3 of the drawings, and in like manner for any other fabric composed of a greater number of layers upon the same principle. As the different threads are thus inserted, they are beaten up in the usual manner.

Where hand-looms are used, which are worked with treadles, there must be more of these treadles than there are heddles, inasmuch as a person with only two feet could not otherwise work three or more treadles at one and the same time. The number of treadles necessary to enable one person to work all the heddles will be found by multiplying the number of heddles by the number of layers. Thus, when there are three heddles, there will be two layers, and the number of treadles will be six. When there are to be three layers, there will be four heddles, and twelve treadles will be necessary, and so on for any greater number of layers.

When hand-looms with treadles are used, and a fabric is to be woven with two layers or courses of weft-threads, the six treadles are to be so arranged as to work the heddles, as below represented, the cardinal numbers "one," "two," and "three," representing the different heddles, and the ordinals "first," "second," &c., the treadles. The working of the different treadles will produce the result thus indicated:

	One.	Two.	Three.
First.	Up.	Down.	Up.
Second.	Down.	Down.	Up.
Third.	Down.	Up.	Up.
Fourth.	Down.	Up.	Down.
Fifth.	Up.	Up.	Down.
Sixth.	Up.	Down.	Down.

With treadles thus arranged and worked by any skillful weaver, the shed may readily be opened so as to

produce the result desired. They will produce that result if depressed in succession in the order above indicated, and may produce it when a different order is observed. Where a fabric with a greater number of layers is to be woven, the treadles may readily be so arranged and worked by any skillful workman as to produce the result desired upon the principles above set forth.

When power-looms are used, the opening of the shed in the same manner may readily be effected, upon well-known principles, and by methods fully understood by every person skilled in the art. They therefore need no further explanation here.

The figs. 1, 2, and 3 in the drawings are more particularly intended to represent curtains manufactured upon this principle, but the operation is substantially the same as in the fabrication of cloth, carpets, or any other material.

a a represent the threads of warp, and *b b* the transverse pieces or the weft, which, it will be seen, form the great body of the fabric. These pieces *b b* are of wood, and are known in the market as match-stuff or sticks, from which friction-matches are made. I arrange these round pieces as above described, so that when woven together, they break joints and form a closely-laid fabric.

It is of course not my intention to confine my invention to the use of wooden strips as the weft, nor to any definite number of layers, as the weft may be composed of cotton, woollen, or other fibrous threads, woven together in the manner above described.

Having thus described my invention, what I claim as new, and desire to secure by Letters Patent, is as follows:

1. I claim the method, herein described, of weaving fabrics having two or more thicknesses of separately-interlocked weft-threads, whereby the upper or lower surfaces are made substantially alike; and so that the fabric presents no right or wrong sides, substantially as above shown.

2. I claim a woven fabric, substantially as described, consisting of two or more layers of separately-interlocked weft-threads, the threads of one layer of weft always lying opposite the spaces between the weft-threads of the layer above or below it, and with all the warp-threads passing from surface to surface, and binding the whole together, as above shown.

E. F. RICHMAN.
